UTILITY CASE

Leopold G. Stanley, Maplewood, N. J.

Application August 4, 1942, Serial No. 453,500

3 Claims. (Cl. 150—28)

This invention is a novel utility case, composed of leather, canvas or similar limp sheet material and of the class adapted to accommodate an unfitted collection or loose kit of small articles or appliances. As one example, the case may be of small size and employed to hold coins, tokens and flat metal or similar contents. As another example, the case may be used to contain toilet articles, brushes, combs, tubes, cutters, etc.; or other kinds of kits may be accommodated, in loose and random manner, as distinguished from the fitted type of case.

The general object of the present invention is to provide a utility case which will be of great convenience of operation in the fields mentioned. A further object is to provide a case which is simple and inexpensive in structure and yet rugged and durable. A particular object is to provide a utility case which may be opened and closed by folding endwise, and is formed with a storage section at one end, for the articles, and a display section at the other end, between which sections the articles may be slid, without danger of spilling, the case nevertheless being of such simple and limp structure that when closed it is exceedingly flat, occupying substantially no more space than that of the accommodated articles.

Other advantages of the invention will appear from the following description of illustrative examples thereof. To the attainment of such advantages the invention consists in the novel utility case and the novel features of construction, arrangement and operation herein illustrated or described.

In the accompanying drawing

Fig. 1 is a face view of the outer or under layer or closed component of the utility case. Fig. 2 is a similar view of the inner or upper layer or apertured member.

Fig. 3 similarly shows the complete case, suitable for coins, the two layers being stitched together and providing the storage half at the left and the display or tray half at the right. Fig. 4 similarly shows the closed condition of the case, the articles having been slid back into the storage end, and the right end bent over and secured by a fastener. Fig. 5 is a longitudinal cross section view of Fig. 3; and Fig. 6 a similar section of Fig. 4.

Fig. 7 in a perspective view shows a larger design suitable as a traveling case, on the same principles, with brushes, cans, etc., slid down into view. Fig. 8 is the same as Fig. 7 but with the goods slid back and roughly arranged within the storage half, ready for closing. Fig. 9 shows

the case of Fig. 8 after being closed and showing the corners of the storage half tucked in under the end rim of the display half, conveniently holding the case closed, without the need of fasteners.

Fig. 10 is a back view showing the manner in which the case of Figs. 7 to 9 may be provided with shoulder straps.

The invention may be outlined specifically as a utility case of the class already referred to, which is composed of outer and inner flat layers of the leather or limp material, of generally oblong outline and peripherally united with each other entirely around such outline; the two layers being substantially uninterrupted excepting that the display zone of the inner layer is formed with an access aperture or open window slightly smaller than the full size of the zone, thereby providing a loose narrow marginal strip standing flatly from the periphery around the end and both sides of the zone and continuous with the material of the margin of the inner layer at the other or storage zone; whereby the toilet or other kit articles may be disposed in the storage section and the flattened display section folded over endwise to close the case, whereas, when the case is open the articles may be slid through between the layers, as by tilting the case, from the storage to the display section, while the marginal strip of the latter flexes upwardly as the goods slide through thereby to constitute an edge rim sufficient to protect the exposed articles against spilling from the case.

Referring to the drawing, Fig. 1 shows the outer or under layer 11, the hinge line 12 of which is indicated, dividing the layer into a left-hand or storage zone 13 and a right hand or display zone 14.

Similarly in Fig. 2 is shown the inner layer 16, as a separate piece of material, although this could, if desired, be integral with the outer layer 11, united therewith along either the short ends thereof or the long sides thereof. Fig. 2 indicates also the hinge line 17 of the inner layer 16, dividing it into the closed or left half or zone 18 and the right hand zone 19, the latter formed with a large access aperture 20, which may be a quadrilateral cut-away area, slightly smaller than the full size of this zone. This aperture or open window 20 is so formed and located as to leave a continuous, narrow and loose marginal strip standing from the periphery, comprising an end strip portion 21 and the opposite side strip portions 22, this entire strip being continuous with

the margin of the remainder of the inner layer at the other or storage zone.

Fig. 3 shows the completely assembled case in open position and Fig. 4 the same in closed position, while Figs. 5 and 6 are the corresponding longitudinal sections; Figs. 3, 5 and 6 showing a number of loose articles or coins C in one or the other of the sections of the case.

By this described arrangement, when the articles are in the storage section, as in Figs. 4 and 6, the display section, now empty and flat, may be folded over endwise to close the case. When the coins are moved into the display section, by tilting, the strip or rim 21, 22 may be assisted in opening by a tab 23 formed on the end strip portion. This tab may be lifted, by hand, when tilting the case; but the side strip portions 22 need no manipulation, since the coins sliding through tend naturally to move partly beneath the side rim portions. A snap fastener socket 25 and stud 26 may be applied to the display zone of the outer layer and the storage zone of the inner layer, respectively, thereby to fasten closed the case as in Figs. 4 and 6. Fig. 6 and others show how the two layers 11 and 16 are united peripherally with each other around the entire outline, a line of stitches 28 being shown for this purpose. When the articles are slid into the display zone, the slight upward flexing of the normally flat marginal strip provides an edge rim, so that the zone acts somewhat as a tray, the rim minimizing the danger of spilling.

Figs. 7 to 9 show on the same principles a canvas case to contain kit objects C larger and thicker than coins, as toilet accessories. The pair of coextensive oblong layers 11 and 16 is united around the periphery. The case is foldable endwise to close it. Both layers are uninterrupted except that the inner layer has the aperture 23 over the major part of its area at one endwise section, constituting it the display section; and this layer has, surrounding the aperture, the marginal strips 21, 22 extending flexibly inwardly from the periphery.

In this larger embodiment, of canvas relatively more limp than leather, the manner of securing it closed may be as shown in Fig. 9. The corner portions 30 of the closed case, at the storage end, are simply tucked inwardly and under the meeting strip portions 21, 22. To provide stiffness and a better finish a narrow leather strip 31 may be stitched at this point to the margin 21. For a walking case or lady's street bag the display end 14 of the outer layer or wall 11 may have straps 33 stitched to it, for support from the shoulder or

waist. The storage section may have a transparent window. In any instance the case is readily opened, selection of contents made, and case closed, with security of contents.

5. What is claimed is:

1. A utility case of limp sheet material adapted to accommodate an unfitted collection or loose kit of small articles or appliances, of the kind having a storage section at one endwise half and a display section at the other half of the case; said case being composed of outer and inner flat layers of generally oblong outline and the two peripherally stitched to each other around such outline, and the display section of the inner layer being formed with an open access window slightly smaller than the section, thereby providing a loose narrow marginal strip instanding from the periphery around the end and both sides of the display section and continuous with the margin of the inner layer at the storage section, and a stiffening element applied along the end marginal strip adjacent said open access window; and the said storage section, by the limp character of the sheet material, being adapted to be crowded and tucked through the access window, within the display section and under the end margin thereof thereby to hold the case closed.

2. A utility case as in claim 1 and wherein is a limp, flexible carrying strap having its ends secured to the outer layer of limp sheet material.

3. A utility case of limp sheet material adapted to accommodate an unfitted collection or loose kit of small articles or appliances, of the kind having a storage section at one endwise half and a display section at the other half of the case; said case being composed of outer and inner flat layers of generally oblong outline, each being formed of a single piece and integral for its full length, and the two being peripherally united around such outline, and the display section having its inner layer formed with an open access window slightly smaller than the section, thereby providing a loose narrow marginal strip instanding from the periphery around the end and both sides of the display section and continuous with the margin of the inner layer at the storage section, and having a stiffening means along the end marginal strip adjacent said open access window; and the said storage section, by the limp character of the sheet material, being adapted to be crowded and tucked through the access window, within the display section and under the end margin thereof thereby to hold the case closed.
